METHOD OF PRODUCING DEEP-DRAWN SHAPES IN SHEET METAL

John H. Engel, Escondido, Calif.

Application July 28, 1952, Serial No. 301,193

9 Claims. (Cl. 113—51)

This invention relates to metal forming or shaping by means of dies, and more particularly to apparatus and procedures for what is commonly known as deep-drawing.

Heretofore, in connection with the deep-drawing or stamping of metal sheets in the usual single step drawing operation, undue stretching and thinning or wrinkling of the metal, especially at sharp bends, have resulted and unsatisfactory products have as a consequence been turned out.

It is an object of this invention to provide a method and apparatus for processing metal sheets, which are eventually to be shaped into deep drawn or crowned or cupped zones or with sharp bends, by first imparting to them a preliminary, moderate shaping by which portions of the metal sheet are so displaced that such preliminary displacement directly facilitates a subsequent shaping operation which normally would be quite severe if the usual drawing procedure were undertaken, but, in view of the preliminary shaping of the present improvement, merely constitutes another relatively mild shaping operation.

I have discovered a method for avoiding the above-described difficulties, which method includes a preliminary partial stretching or shrinking, as the case may be, so that the metal sheet is preshaped to an intermediate stage, such preliminary shaping facilitating a subsequent or final shaping without undue stretching, or thinning, or buckling or wrinkling of the metal sheet at any place in any significant degree.

Another object of this invention is to simplify all deep-drawing procedures and kindred shaping procedures wherein the plural stage operations of this invention will yield improved shaped products.

Other objects of the invention are to make it possible to employ in any given connection smaller dies to obtain faster production, to reduce material losses by reason of elimination of damage to metal sheets undergoing drawing, to permit the use of cheap blanking dies, to reduce die shifting, to reduce shear-strain on equipment and procedures, to provide for wider use of the various metals, to permit the employment of metal sheets of thinner gages for yielding structures of less weight, to improve the structural condition of the product, to permit hot forming of some metals, and to permit the use of softer metals or other materials for dies in some operations such as hydro-pressing.

Another object of the invention is to provide a method for deep-drawing and similar metal shaping whereby stretching, wrinkling, shrinking and the like may be uniformly controlled and in a predetermined manner, wrinkling, stretching or shrinking being effected in predetermined directions as best required to provide for the final shaping operation whether such final operation be a stretching operation or effectively a shrinking operation.

It is a still further object of the invention to provide for a preliminary wrinkling or waving of the metal sheet which is finally to be shaped into a given product,

2

such wrinkling or waving preferably being effected in general correspondence with the nature of the final shaping of the sheet, whether such shaping be by stretching or shrinking operations.

It is a still further object of the invention to employ a flexible, preferably non-stretchable, or only slightly stretchable, set, pattern material which has been shaped to conform exactly with the final product as by shaping to the final male or female die, such flexible, substantially non-stretchable pattern being then shaped into a desired wrinkle formation, as through the medium of any retaining means such as modeling clay, from which a pattern may be made for an intermediate or preforming die by means of which preforming die the sheets to be shaped will be given preforming treatment prior to final shaping in finish dies.

Other objects of the invention, and the various novel features thereof will become apparent to those skilled in the art upon reference to the following specification and the accompanying drawings wherein certain embodiments are illustrated.

In the drawings, wherein the deep-drawing of a relatively simple shape is illustrated:

Fig. 1 represents a side elevation of a male finish die superimposed over a female finish die having the shape to be produced in the final product;

Fig. 2 illustrates diagrammatically the production of a flexible, relatively non-stretchable pattern from the male die member;

Fig. 3 indicates in vertical cross section a step of associating the pattern produced in Fig. 2 with retaining means such as modeling clay to be relied upon in a subsequent shaping operation;

Fig. 4 indicates in a vertical cross section the shaping by waving of the flexible, substantially non-stretchable pattern of Figs. 2 and 3 through the medium of relatively stiff modeling clay;

Fig. 5 indicates diagrammatically how the curved structure of Figs. 2 and 3, which might be hemispherical, is related to the waves of Fig. 4;

Fig. 6 is a fragmentary detail in plan showing a woven fabric imbedded in set latex material (or the like) of which the pattern is formed, a portion of the imbedding material being broken away to reveal the fabric;

Fig. 7 is a cross sectional detail taken on the line 7—7 of Fig. 6;

Fig. 8 is a sectional detail indicating modified means (small tacks) of effecting the configuration of the flexible non-stretchable pattern;

Fig. 9 is illustrative of both a male plaster mold and preforming die, made therefrom, superimposed over a corresponding female mold and preforming die made therefrom, these having been produced from the shaped pattern of Fig. 4 or of Fig. 8;

Fig. 10 illustrates a method of shaping a metal sheet from the female die of Fig. 9 through the medium of a heavy rubber blanket disposed above the metal sheet and a flat hammer superimposed above the rubber blanket;

Fig. 11 indicates the action of the flat hammer of Fig. 10;

Fig. 12 is a plan view of the preformed metal sheet of Fig. 11, and consequently is also a plan view of the female die with which it was formed and of the flexible pattern;

Fig. 13 illustrates a final shaping operation upon the preformed sheet of Fig. 12;

Fig. 14 is an inner face view of the finally shaped article indicated in Fig. 13;

Fig. 15 is a perspective view illustrating the drawing of a more complicated article wherein the final product has sharp corners;

Fig. 16 is a fragmentary sectional detail showing the use of a thin liner or stage die in a finish female die to provide an intermediate curve at the sharp shoulder position of Fig. 15, an intermediate male die being employed; and

Fig. 17 is a sectional detail indicating a final operation in producing a sharp shoulder with the two finish dies after the liner or stage die of Fig. 16 has been removed.

In practicing this invention, a finish male die 10 and a finish female die 12, illustrated in Fig. 1, will have been manufactured to produce the required product. Either of the finish dies 10 and 12, but preferably the male die 10 is used in the nature of a pattern to form thereon an accurate set, flexible, relatively non-stretchable pattern 15 indicated in Fig. 2. This pattern 15, which includes a large crowned or cupped zone, is made up of appropriate fabric 16, such as cheesecloth, and an appropriate setting material 18 which is flexible when set, such as latex or is made without cheesecloth, but with a heavier layer of latex so as to minimize stretching. In building the pattern 15, latex gum or other appropriate form of rubber in the non-set state is first applied to the shaping surface of the male die. A sheet of cheesecloth is then applied to the unset latex and pressed down into the same, or if necessary a number of pieces of cheesecloth are applied to the latex in various positions and in overlapping relationship, so that the shape of the forming member of the die is attained by the applied cheesecloth. Preferably, additional latex is applied over the positioned cheesecloth (and a second layer of cheesecloth is positioned) whereupon another layer of the latex material is applied. This operation is readily effected manually and the latex and cheesecloth layers so worked that the layers are thoroughly saturated with the latex and one uniform whole is produced which exactly conforms to the shape of the forming portion of the die. This pattern member is then allowed to set on the die. When thoroughly set, the pattern member 15 is readily stripped off from the die. The layers of cheesecloth used are adequate to render the pattern 15 non-stretchable in any direction, although the latex and bedding material render the pattern flexible so that it may be shaped into a plurality of wrinkles as best indicated in Fig. 4.

For the purpose of simplicity, the forming member of the male die 10 is considered to be a portion of a sphere, the pattern 15 therefore being circular, as is the pre-formed metal sheet of Fig. 12 and the finally shaped product of Fig. 14.

In order to produce a preforming die, such as seen in Fig. 10, from the cupped pattern 15, the latter is placed upon an appropriate support 20 (Figs. 3, 4 and 8), and the cup portion is then rather carefully worked into a series of wrinkles or waves 22 as seen in Fig. 4. In the case of the partially spherical structure illustrated, these wrinkles may desirably be in the form of circular concentric waves. It is necessary of course that the position of these concentric waves be maintained in order that plaster casts or the like may be made from which to produce the required preforming die or dies such as illustrated in Fig. 9. In Figs. 3 and 4 the means employed for retaining the shape of the waves 22 is in the form of modeling clay 24 or the like. This clay is rather readily shapable by the fingers of the operator as the waves are being produced in the fabric body of the pattern 15. Having thus been shaped, the waves or wrinkles readily maintain themselves in conjunction with the conforming shapes in the modeling clay. If essential, very small tacks such as indicated at 25 may be placed at the bottoms of the waves and driven into the base 20 which may be a wood base. Commonly such tacks are not necessary. Another method for maintaining the wrinkles or waves 22 in the pattern 15 is illustrated in Fig. 8 where flat headed tacks 26 are employed to anchor the bottoms of the wrinkles. In practice the heads of these tacks will be imbedded in the fabric-latex layer so as not to interfere appreciably with the subsequent forming of castings for the preform-

ing dies. Of course, in more complex structures, the waves or wrinkles produced in the cupped pattern 15 will be quite variable and may be quite irregular according to the shape of the pattern and the final product to be obtained. If necessary to provide a marginal retainer to facilitate shaping, such as indicated at 28 in Fig. 4, such may be employed, although probably this will not be necessary.

By reference to the diagrammatic indication of Fig. 5, 10 wherein a 120° segment is illustrated representing an elongation of about 20% of the arc, it will be seen that, when the cup portion of the pattern 15 is pressed down and the waves or wrinkles 22 formed, the elongation is taken up by the resultant undulations. This is true not only on the diameter indicated in Fig. 5, but also on the circles indicated in Fig. 12.

Having shaped the cupped pattern 15 to provide appropriate waves or wrinkles 22 as seen in Fig. 4, this shaped pattern is then employed for the casting thereupon of a plaster or other appropriate mold, from which the necessary preforming dies are produced. Thus a plaster cast 30 representing a preforming female die may be formed, and a plaster cast 32 representing a preforming male die may also be formed. These casts 30 and 32 are then used 25 as molds to produce the required preforming dies. Both a male die and a female die may be used (of which also Fig. 9 may be considered representative), or, as indicated in Figs. 10 and 11, a female die 35 may be employed in conjunction with a typical rubber blanket or pad 36 and a flat hammer 38 which may have a pad-retaining flange 39 if necessary or desirable. By means of such flat hammer 38 and the rubber pad 36, which is formed from a tough, fairly hard rubber having a Shore hardness of 40 to 90 or harder (and corresponding generally with truck tire tread stock), a blow of the flat hammer 38 causes the metal sheet 40, which has been inserted in the position shown in Fig. 10, readily to assume the shape of the female die by reason of distortion of the rubber pad 40, as shown in Fig. 11. The preformed metal sheet 40 thus formed has waves or wrinkles 42 corresponding with the waves or wrinkles 22 of the pattern 15, as illustrated in both Figs. 11 and 12. This is substantially the same shape that would have been imparted by employing a preforming male die in conjunction with a preforming female die 35.

By employing the intermediate preforming procedure described, it is possible to use softer materials for the preforming dies than for the finish dies. It would even be possible to employ a preforming male die of lead or of a plastic material in conjunction with a female die 35 which probably would preferably be produced of a harder material.

Having preformed the sheet 40 to such a shape as indicated at 42 in Fig. 12, it is then passed to the finish dies of Fig. 1, as shown in Fig. 13 wherein the female finish die 12 is employed with the male finish die 10, the finally shaped metal article 50 produced from the pre-formed sheet 42 being shown in position in the female die 12 and being separately shown in face view in Fig. 14. It is desirable in some instances to employ a rubber blanket 55 interposed between the finish dies 10 and 12 in producing the finished article 50 whereby best to produce the final displacement.

Much more complicated shapes may, of course, be produced than that above described. Representatives of such shapes is the shape 60 seen in Fig. 15, wherein deep-drawn cupped portions run off at various angles to one another and sharp shoulders are to be produced at 62, flanged portions 64 being required in the final shape. 65 In producing this shape various wrinkles and waves will be formed in the flexible, relatively non-stretchable pattern which will have been produced to conform with the final shape required, such pattern having been made as above described in connection with the pattern 15. Additionally, in the first preforming operation small wrinkles

may have been produced in the flanged portions 64 such as indicated at 65, these being the result of an initial contrasting effect, such contraction to be completed in a final forming stage. In this case, it is desirable to form the sharp shoulders in two stages of the final shaping operation, following the preforming operation. For this purpose a liner die 70 (Fig. 16) will be used in the finish die 75 so that when a cooperating die 76 is brought down, the shoulder 62 will be formed as a rounded shoulder rather than as a sharp shoulder. Thereafter, a cooperating finish die 78 will be used with the lower finish die 75 to complete a sharp shoulder in the product 60 as seen in 62a in Fig. 17.

From the foregoing description it will be apparent that I have provided a method and means for producing shapes, especially deep-drawn or cupped or crowned shapes, which avoid over-stretching and thinning out of sheet material from which the shapes are being formed, such method including essentially a preforming operation, by means of which intermediate shaping is produced as by the formation of waves or wrinkles so as to displace starting material in a general plane or zone which is relatively flat or shallow as compared with the final deep-drawn product, the metal of the sheet being displaced in such preforming operation in directions and in a manner dissimilar to those of the final shape, the final shape being thereafter produced in a separate operation by finish dies which may be of conventional type. As a consequence of such intermediate or preforming operation, dies of softer material may be used for the preforming step, complete accuracy of manufacture of such preforming dies being unnecessary in view of the fact that such preforming step is an intermediate operation. The usual, accurate finish dies which are employed in the final step have a considerably longer life than where complete shapes are formed in one operation. Also the savings resulting from the spoilage of much starting material, as has heretofore resulted, are of very great significance. In addition the amount of highly skilled labor normally required is by this method very materially reduced.

Not only may softer metals than usual be employed for the preforming dies than are required for finish dies, but, for some uses, hard plastics and the like may also be used. If two preforming dies are employed for a given operation, it is feasible to make the male die of a material such as lead for many uses.

Sheets which may be readily drawn to yield true, uniform, and accurate products, without spoilage, are represented by aluminum alloys, magnesium alloys, stainless steels, and the like. Where final products of distinctly irregular shape are to be drawn, such as illustrated in Fig. 15, it is apparent that in wrinkling or waving, at least in portions thereof, the pattern 15 must be shaped with fine waves or wrinkles of varying sizes and extending in varying and irregular directions according to the final shape required. Such methods are readily learned by operators of ordinary skill or of even less skill than that frequently required in conventional deep-drawing operations.

This process permits the employment of lighter and thinner materials than it has heretofore been possible to use in contoured stampings and the like; also magnesium or titanium sheets may be readily used with necessary controlled heating, as by employing heated rubber pads in connection with the preforming operation. Thus, the natural characteristics of both the process and the magnesium sheet undergoing elongation with controlled heating, provide great possibilities in corresponding large complicated stampings, and in addition reinforcements and auxiliary or complicated assemblies are avoided. These advantages offer great aid to the manufacture of lighter and more efficient aircraft and the like.

I claim as my invention:

1. A method for producing deep-drawn shapes in metal sheets, including: forming a flexible pattern having a cupped portion of the final shape required; shaping said cupped portion of the flexible pattern into a series of waves disposed in a generally flatter zone than the final shape required while avoiding increase in the projected area of the pattern; producing a preforming die conforming with said shaped flattened cupped portion of said flexible pattern; shaping a metal sheet from said preforming die, thereby partially stretching and shrinking and partially shaping said sheet; and thereafter subjecting such preformed sheet to the action of finish dies to yield the final shape required.
2. A method for producing shapes from metal sheets, including the steps of: forming a flexible, relatively non-stretchable pattern conforming with the final metal shape having a cupped portion desired; shaping said flexible pattern by flattening said cupped portion to provide a series of wrinkles in a flatter region than the final shape while avoiding increase in the projected area of the pattern; positioning said shaped pattern for casting; producing a cast mold conforming with said flattened shaped pattern; producing a preforming die from said cast mold and conforming therewith; operating upon a metal sheet with said preforming die and thereby partially shaping said sheet; and thereafter subjecting such partially shaped sheet to the action of a finish die to complete the desired metal shape.
3. A method as in claim 2 including the step of employing a yielding putty-like material in shaping said flexible pattern to retain the wrinkled condition produced therein.
4. A method for producing deep-drawn shapes in metal sheets, including: forming a now-expanding flexible pattern having a cupped portion of the final shape required; shaping by depressing the cupped portion of the flexible pattern toward a flat plane into a series of wrinkles without material increase in the projected area of the cupped portion of the pattern and of the final shape and in a relatively flat wrinkled zone compared with the final deep-drawn shape; producing a preforming die conforming with said flattened wrinkled pattern of such limited area; preshaping a sheet of metal with said preforming die to conform with such die and thereby partially shaping said sheet; and thereafter shaping the preformed sheet with a finish die to yield the finally required cupped shape.
5. A shaping method as in claim 4 wherein the flexible pattern of the final shape is dome-like and the wrinkles are annular.
6. A method as in claim 4 wherein said preshaping is effected by disposing said metal sheet between a tough rubber blanket and said preforming die, said blanket holding said sheet, and then imparting drop-hammer impact to said sheet through said blanket to accomplish said preshaping.
7. A method as in claim 4 wherein putty-like material is disposed in the wrinkles produced in depressing said cupped pattern to maintain uniform surfaces of said wrinkles and avoid collapse thereof.
8. A method as in claim 4 wherein a plaster cast is produced from said flattened wrinkled shape and said preforming die is produced from said plaster cast.
9. A method for producing deep-drawn shapes in metal sheets, including: forming a flexible pattern of a final shape desired having a cupped portion; shaping the cupped pattern portion by depressing the same toward a flat plane while forming a plurality of wrinkles; producing a preforming die from and conforming with said wrinkled depressed pattern portion; producing a preformed metal sheet from such preforming die; placing such preformed metal sheet between male and female finish dies; disposing a heavy rubber blanket on such preformed sheet in position spanning the female die and 75 in position retaining the preformed sheet; and shaping

such sheet by such finish dies with said blanket interposed to yield the final deep-drawn shape required.
